(57) **CLAIM**

The ornamental design for a centralizer, as shown.

DESCRIPTION

FIG. 1 is a perspective view of a centralizer connected to the tabs. The tabs extend inwards, toward one another, and the engaging rings are disposed axially-intermediate of the tabs. FIG. 2 is an end view of the centralizer. FIG. 3 is side view of the centralizer.

FIG. 4 is a perspective view of the centralizer disposed on an oilfield tubular (e.g., casing or drill pipe). A stop collar is disposed axially-intermediate of the engaging rings. FIG. 5 is a side view of the centralizer, showing axially-extending seams thereof positioned circumferentially between the tabs.

FIG. 6 is an end view of the centralizer of FIG. 5, showing the radial-extension of the seams. FIG. 7 is a side view of the centralizer, showing two of the axially-extending seams extending across the tabs.

FIG. 8 is an end view of the centralizer of FIG. 7, showing the radial-extension of the seam; and, FIG. 9 is a side view of the centralizer, showing offset, axially-extending seams thereof. The end view of the centralizer of FIG. 9 is shown in FIG. 6.

The broken lines in the drawings depict unclaimed environmental subject matter.

1 Claim, 6 Drawing Sheets
